UNITED STATES PATENT OFFICE.

HANS SCHWEITER, OF HOREGEN, SWITZERLAND.

CROSS-WINDING MACHINE.

Application filed March 29, 1922. Serial No. 547,839.

To all whom it may concern:

Be it known that I, HANS SCHWEITER, a Swiss citizen, residing at Horgen, in the Canton of Zurich, Switzerland, have invented a new and useful Improvement in Cross-Winding Machines, of which the following is a specification.

This invention relates to cross winding machines in which a spool is rotated by means of a friction drum provided with a groove for driving the thread guide.

The main object of my invention is to provide a machine which has a higher efficiency than those hitherto known and in which there is less wear of the working parts.

I attain these objects by the mechanism illustrated in the accompanying drawings, in which—

20 Figures 1 and 2 which are respectively an elevation and a left hand side view of the cross winding machine.

Figure 3 is an enlarged section on line 3—3 of Figure 1.

25 Figures 4 to 6 are respectively an enlarged side view, a plan and a vertical section of the thread guide.

Figure 7 is an enlarged detached detail view of Figure 2.

30 Figure 8 is a vertical section on line 8—8 of Figure 7.

Figure 9 is a horizontal section on line 9—9 of Figure 2, drawn to a reduced scale.

35 Figures 10 to 12 are respectively an enlarged side view, a plan and a vertical section of a double thread guide.

The rotated drum 1 has a driving groove 2 for the thread guide 3, located at an incline to the drum axis and the rear side of 40 the thread guide 3, is so curved that it fits the rounded contour of the drum.

A cylindrical projection 4 forced out of 45 the rear wall of the hollow thread guide 3 engages the driving groove 2 of the drum.

45 The front wall of the thread guide is connected by a rib with the rear wall and has a vertical open groove 5, for the guidance of the thread 6. The substantially circular thread guide 3 terminates at the bottom in 50 a flat portion and thus a sharp edge 7 substantially perpendicular to the thread is produced where the thread leaves the groove 5 whereby any tendency of the thread to ride up the edges of the lower end of the groove 5 and leave the groove laterally during the 55 to and fro movement of the thread guide

is overcome. The front wall of the latter has further an open groove 8 for the reception of a guide rod 9 which retains the thread guide in position on the drum during its to and fro movement. The front wall 3 is so curved that the thread during the first to and fro movement of the guide will enter the groove 5 automatically and that on pushing the guide into its working position from below, the resilient guide rod 9 will be forced outwardly by the guide and then spring into the groove 8 whereby fixing of the guide on the drum is considerably facilitated. In order to remove the 70 thread guide from the drum, all that is necessary is to slightly bend the rod 9 outwardly and to slide the guide upwards or downwards. Owing to the weight of the metal thread guide being only about two 75 grammes, it can operate without shocks and noise at a very high speed, whereby the efficiency or output of the machine is considerably increased.

The guide rod 9 is carried by two adjustably fixed arms 11, Figures 2 and 7 to 9, and by angular adjustment of the arms 11 on the shaft 10, the distance of the rod 9 and therefore of the thread guide from the place of contact of the spool 12 or material 12' (Figure 3) wound on the spool with the drum 1 can be varied.

In order to permit of regulating the distance between the guide rod 9 and the drum and thereby the degree of contact of the 90 thread guide with the drum, each end of the rod is mounted in a radial slot 13 in a cylindrical part 14 mounted in the respective arm 11.

The slot 13 is engaged by a short tongue 95 15 provided on a plate 17 which rests on the part 14 and is formed with a slot 16 (Figures 7 and 8). By adjustment of this plate on arm 11, the part 14 is turned in the arm 11 and the rod 9 is thereby caused to approach or recede from the drum 1. After the rod 9 has been set at the correct distance from the drum it is locked in position by tightening screws 18 which engage the slot 16 of the plate 17 and by tightening a nut 19 which screws on the part 14. The nut 19 is locked by engagement in the groove 21 of the nut, of the forked channel like and resilient ends 20 on the plate 17.

Figures 13 and 14 show a thread guide 3^a 110 which is separated by a partition 30^a into two grooves 5 and 5^a for two threads where-

by the right thread automatically enters the right hand groove 5^a when the guide moves towards the right and the left thread automatically enters the left groove 5 when the guide moves towards the left. Instead of the thread guide being hollow it may be solid.

I claim:—

1. In a cross winding machine adapted to 10 rotate a spool by means of a friction drum provided with a driving groove for a thread guide, a thread guide consisting of a very light member adapted for very high speeds and bearing with its rear side direct against 15 the drum; at least one open groove in the front side of the guide to guide the thread; a guiding and holding member for the guide; and an open groove in the front side of the guide for the reception of the said 20 guiding and holding member.
2. In a cross winding machine adapted to rotate a spool by means of a friction drum provided with a driving groove for a thread guide, a thread guide; and a resilient rod 25 adapted to serve as a guide for the thread guide and removably hold it in sliding contact with the periphery of the drum.
3. In a cross winding machine adapted to 30 rotate a spool by means of a friction drum provided with a driving groove for the thread guide, a thread guide; a groove in the front of the thread guide; a resilient holder for the guide; and a curved front 35 surface on the thread guide adapted by the sliding movement of the guide to automatically cause the thread to enter the said groove and to facilitate fixing and removal of thread guide on and from the drum by a bending of the resilient holder.
4. In a cross winding machine adapted to 40 rotate a spool by means of a friction drum provided with a driving groove for a thread guide, a thread guide; a thread groove in the thread guide; and a flat side on the 45 thread guide parallel with the drum axis and facing the spool, whereby the thread is

prevented from accidentally slipping out of the guide groove.

5. In a cross winding machine having a spool rotated by friction from a drum provided with a driving groove for a thread guide, a thread guide; and a curved rear surface on the thread guide directed towards and conforming with the curvature of the drum. 55

6. In a cross winding machine having a spool rotated by friction from a drum provided with a driving groove for a thread guide, a thread guide; a stamped sheet metal piece forming one part of the thread guide; 60 guide grooves in said piece; a stamped sheet metal piece forming the other part of the thread guide and secured to the first named piece by a folding; and a projection on the second named piece adapted to engage the 65 driving groove of the drum.

7. In a cross winding machine having a spool rotated by friction from a drum provided with a driving groove for a thread guide, a thread guide; two thread guiding 70 grooves therein; and a partition separating the two grooves.

8. In a cross winding machine having a spool rotated by friction from a drum provided with a driving groove for the thread 75 guide; a thread guide; a guiding and holding member for said thread guide; and adjusting means whereby said member can be adjusted relative to the drum.

9. In a cross winding machine having a spool rotated by friction from a drum provided with a driving groove for a thread guide, a thread guide; a guiding and holding member for said thread guide; and adjusting means whereby said member can be 80 adjusted, about the drum axis.

Signed at Zurich, in the Canton of Zurich, Switzerland, this 10th day of March, 1922.

HANS SCHWEITER.
